United States Patent Office

Des. 213,460
Patented Mar. 4, 1969

213,460

CUP

Charles F. Beckman, Chicago, and Robert W. Schier,
Glenview, Ill., assignors to Nibot Corporation, Chicago,
Ill., a corporation of Illinois

Filed May 14, 1968, Ser. No. 11,910

Term of patent 14 years

U.S. Cl. D44—9
Int. Cl. D7—01

FIG. 1

FIG. 2 is a top plan view thereof; and

FIG. 3 is an enlarged scale cross-sectional view thereof along the line 3—3 of FIG. 1.

The bottom of the cup is plain and unornamented.

We claim:

The ornamental design for a cup, substantially as shown and described.
